Primary Examiner — Amy C Wierenga(74) *Attorney, Agent, or Firm* — Calfee Halter & Griswold LLP(57) **CLAIM**

We claim the ornamental design for the bridge piece, as shown and described.

DESCRIPTION

FIG. 1 is a front-right-top perspective view of the bridge piece showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dot broken lines represent the bounds of the claimed design, while all other, uniformly broken lines are directed to environment and are for illustrative purposes only. Both the dash-dot and uniformly broken lines form no part of the claimed design.
